CLAIM

An ornamental design for a tray for packing foods, reference being made to the accompanying drawings, forming a part thereof.

DESCRIPTION

FIG. 1 is a perspective view in the open configuration of a tray for packing foods.

FIG. 2 is a perspective view in the closed configuration of a tray for packing foods.

FIG. 3 is a top view in the open configuration of a tray for packing foods.

FIG. 4 is a bottom view in the open configuration of a tray for packing foods.

FIG. 5 is a right side view in the open configuration of a tray for packing foods, the left side view is a symmetric image thereof.

FIG. 6 is an end view of the top portion of a tray for packing foods. In the closed configuration, FIG. 6 as shown forms the upper portion of a front end view. In the open configuration, the top portion has been rotated and the corresponding perspective illustrated in FIG. 6 would be rotated; and, FIG. 7 is a front end view of the lower portion in the open configuration of a tray for packing foods.

The broken lines in the figures illustrate portions of the design that form no part of the claimed design.
